UNITED STATES PATENT OFFICE

CHARLES F. SMITHSON, OF ELKRIDGE, AND GEORGE C. OWENS, OF RELAY, MARYLAND

FIGURE TOY

Application filed April 28, 1931. Serial No. 533,488.

This invention relates to figure toys and more especially of a wheel type, and it is an object of the invention to provide a device of this kind simulating an animal drawn vehicle wherein means are provided to effect movement of the animal figure independently of the travel of the toy or device.

It is also an object of the invention to provide a device of this kind including a figure having parts mounted for movement together with means operating when the device is in transit for effecting the desired movements of such parts.

Furthermore, it is an object of the invention to provide a device of this kind which includes a figure in simulation of a draft animal together with means whereby, when the device is in transit, the figure is caused to have movement in imitation of an unruly or kicking animal.

A still further object of the invention is to provide a device of this kind which includes in its structure a figure in simulation of a driver together with means in operation during the travel of the toy to cause said figure to simulate a whipping action with respect to a draft animal figure also included in the device.

The invention consists in the details of construction and in the combination and arrangement of the several parts of our improved figure toy whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:—

Figure 1 is a view partly in side elevation and partly in section illustrating a figure toy

constructed in accordance with an embodiment of our invention;

Figure 2 is a view in bottom plan of the structure as illustrated in Figure 1;

Figure 3 is a detailed sectional view taken substantially on the line 3—3 of Figure 1; 50

Figure 4 is a detailed sectional view taken substantially on the line 4—4 of Figure 1;

Figure 5 is a detailed sectional view taken substantially on the line 5—5 of Figure 1; 55

Figure 6 is a detailed sectional view taken substantially on the line 6—6 of Figure 4.

As disclosed in the accompanying drawings, B denotes an elongated base or body member of desired design or configuration 60 and which is provided at its rear portion with the upstanding side walls 1 and the back cross wall 2.

The rear portion of the base or body member B adjacent to the sides thereof is provided with the depending bolsters 3 which are mounted upon and suitably held to the transversely disposed axle or shaft 4, the central portion of which is provided with a crank 5 of a desired throw. Fixed to the outer extremities of the shaft 4 and positioned in close proximity to the opposite sides of the body member or base B are the ground engaging wheels W. As the device is drawn over a suitable supporting surface the resultant rotation of the wheels W effect the desired rotation of the shaft 4. 75

The front end portion of the base or body member B has freely disposed therethrough from below a shank 6 carried by a conventional fork 7. This fork 7 provides a mounting for the forward ground engaging and steering wheel S. The shank 6 together with the fork 7 are free to rotate with respect to the base or body member B. Pivotally engaged, as at 8, with the upper or free end portion of the applied shank 6 is an elongated handle member 9 providing means whereby the device may be readily drawn or pulled. 90

The side walls 1 of the base or body member B provide a supporting structure for a transversely disposed seat 10 upon which is placed a figure member 11 in simulation of a person in a sitting posture. This figure member 11 is provided with a depending post 12 extending from above through a suitably positioned opening 14 through the seat 10.

10 The applied post 12 has disposed therethrough a cotter pin 15 or the like which also preferably contacts from below with the seat 10 whereby the figure member 11 is effectively anchored in desired position upon 15 the seat 10.

Pivoted supported, as at 16, at the lower part of the applied post 12 is a rearwardly disposed rock arm 17 and to the outer or free end portion of this rock arm 17 is operatively engaged a rod 18 which in turn is operatively connected, as at 19, with a member 20 in simulation of one of the arms for the figure member 11. This member or arm 20 is freely mounted for rocking movement 25 upon a pin 21 disposed through the upper portion of the figure member 11. The outer extremity or hand portion of the member or arm 20 is provided with a socket 22 through 30 which is insertable an end portion of an elongated flexible rod or wire 23 in simulation of a whip. It is to be understood that any means or arrangement may be employed to effect the desired attachment of the rod 23 with respect to the member or arm 20.

35 Depending from the pivoted end portion of the rock arm 17 is an elongated arm 24 which extends below the base or body member B through a suitably positioned elongated slot 25. This arm 24 below the base or body 40 member B is continued by a laterally or transversely disposed extension 26 for contact from above with an elongated pitman rod 27.

One end portion of this pitman rod 27 is operatively engaged with the crank 5 carried by the shaft 4 while the opposite end portion of the pitman rod 27 is freely disposed through a loop or eye member 28 carried by the outer extremity of a downwardly disposed rock arm 29. This rock arm 29 is 50 rotatably mounted upon a pin 30 connecting and bridging the space between the posts 31 disposed through the base or body member B from above. These posts 31 are spaced apart transversely of the base or body member and 55 depend from the upstanding leg sections 32 positioned upon the base or body member B. Disposed through the posts 31 for contact from below with the base or body member B is a pin 33 thus providing means for effectively maintaining the upstanding leg members 32 in desired assembly. Received between the upper portions of the leg members 32 and pivotally connected therewith by a pin 34 or the like is a part 35 depending from 60 the forward portion of a figure member 36, in

simulation of a draft animal. This pivotal mounting permits the figure member 36 to have rocking movement in a vertical direction or in a direction toward or from the base or body member B.

The rock arm 29 hereinbefore mentioned has movable therewith a second rock arm 37 herein disclosed as disposed upwardly and forwardly with respect to the base or body member B, and operatively connected with 75 this rock arm 37 is an elongated rod 38 which is also operatively engaged with the forward portion of the figure member 36 or that portion 36a simulating the head of the draft animal.

The forward end portion of the pitman rod 27 is returned, as at 39, to provide what may be termed an elongated loop member whereby the pitman rod 27 in its movements as effected by the crank 5 will, during the 85 major portion of its movement in either direction, travel independently of the rock arm 28, but just before said pitman rod reaches the limit of its rearward movement the part 40 of said rod affording connection with the returned portion 39 will have sudden or abrupt contact with the rock arm 28, thus resulting in a sudden and abrupt upward rocking movement of the rear portion 90 of the figure member 36 whereby will be 95 closely imitated the antics or action of an unruly or kicking animal. As the pitman rod 27 is moved forwardly the rear portion of said rod will also be raised, as indicated by broken lines in Figure 1, and such upward or raising movement of the rod 27 will result in contact with the transverse or lateral extension 26 of the arm 24 resulting in a downward swinging movement of the arm 20 whereby is closely imitated a whipping 105 action upon the figure member 36 of the rod 23.

As the rod 27 swings downwardly as the crank 5 passes from above beyond the vertical the weight of the arm 20 will cause the elongated rod 24 to swing downwardly and rearwardly whereby the whipping action of the rod 23 is further completed or simulated. It is also to be stated that after the sudden action of the rod 27 upon the rock arm 28 115 to throw upwardly the rear portion of the figure member 36, said figure member 36 will return to its down or normal position under its own weight and, of course, the rock arm 28 will be returned to its normal forwardly and downwardly disposed position.

Pivoted connected, as at 41, with the opposite side portions of the lower part of the figure member 36 are the upper rear leg sections 42 to the lower or free end portion of each of which is pivotally connected, as at 43, a lower rear leg section 44 which, when the figure member 36 is in its lowered or normal position, has direct contact from 125 above with the base or body member B. To 130

the upper portion of each of the rear leg sections 42 and at a point in advance of its pivotal mounting 41 is secured an end portion of a rod 45, the opposite end portion 5 of which being suitably secured to one of the leg sections 32 below the pivotal mounting 34. This rod 45, as the rear portion of the figure member 36 is thrown upwardly, results in the associated rear leg section to further simulate 10 the kicking action of the draft animal as clearly indicated by broken lines in Figure 1.

With respect to the rod 18 it is to be noted that the same possesses sufficient flexibility to offer no hindrance or obstruction to the desired 15 rocking or swinging movement of the arm 20 and for which reason the pivoted end portion of the arm 20 is rounded, as indicated at 46 in Figure 6 of the drawings.

To the side of the figure member 11 opposite 20 to the arm member 20 the pin 21 pivotally supports a second rock member 47 also in simulation of an arm for the figure member 11 and to the outer or hand portion of this member or arm 47 is suitably secured a 25 flexible member 48 in simulation of conventional reins.

From the foregoing description it is thought to be obvious that a figure toy constructed in accordance with our invention is 30 particularly well adapted for use by reason of the convenience and facility with which it may be assembled and operated, and it will also be obvious that our invention is susceptible 35 of some change and modification without departing from the principles and spirit thereof and for this reason we do not wish to be understood as limiting ourselves to the precise arrangement and formation of the several parts herein shown in carrying out 40 our invention in practice except as herein-after claimed.

We claim:—

1. A device of the class described comprising 45 a base member, a crank shaft having means for rotating the same, a figure member pivotally mounted on the base member, a rock arm mounted upon the base member, an operative connection between the rock arm and the figure member to rock the figure 50 member in one direction upon movement of the rock arm in one direction, and a pitman rod operatively engaged with the crank shaft and having a loop like portion freely engaged with the rock arm, said loop portion 55 permitting limited movement of the pitman rod with respect to the rock arm but engaging the rock arm to effect an abrupt movement of the rock arm upon nearing the completion of the movement of the pitman 60 rod in one direction.

2. A device of the class described comprising 65 a base member, a crank shaft having means for rotating the same, a figure member pivotally mounted on the base member, a rock arm mounted upon the base member, an

operative connection between the rock arm and the figure member to rock the figure member in one direction upon movement of the rock arm in one direction, a pitman rod operatively engaged with the crank shaft 70 and having a loop like portion freely engaged with the rock arm, said loop portion permitting limited movement of the pitman rod with respect to the rock arm but engaging the rock arm to effect an abrupt movement of the rock arm upon nearing the completion of the movement of the pitman rod in one direction, leg members pivotally engaged with the figure member, and means co-acting with said leg members to cause the 80 same to have independent swinging movement with respect to the figure member upon pivotal movement of the figure member.

3. A device of the class described comprising 85 a base member, a swinging member pivotally mounted thereon, a crank shaft carried by the base member and having means for rotating the same, a pitman rod operatively engaged with the crank shaft and also operatively engaged with the swinging member 90 to effect rocking movement of the swinging member during the rotation of the shaft, a second swinging member, a rock arm carried by the base member and operatively engaged with the second swinging member, and an elongated arm movable with the rock arm, said elongated arm being engaged by the pitman rod in its movements to effect the desired rocking of the rock arm to operate 95 the second swinging member. 100

4. A device of the class described comprising 105 a base member, a swinging member pivotally mounted thereon, a crank shaft carried by the base member and having means for rotating the same, a pitman rod operatively engaged with the crank shaft and also operatively engaged with the swinging member to effect rocking movement of the swinging member during the rotation of the shaft, a second swinging member, a rock arm carried by the base member and operatively engaged with the second swinging member, 110 an elongated arm movable with the rock arm, said elongated arm being engaged by the pitman rod in its movements to effect the desired rocking of the rock arm to operate the second swinging member, the weight of the elongated arm providing gravity means for moving the second swinging member in one direction. 115

5. A device of the class described comprising 120 a base member, a crank shaft having means for rotating the same, a figure member pivotally mounted on the base member, a rock arm mounted upon the base member, an operative connection between the rock arm and the figure member to rock the figure member in one direction upon movement of the rock arm in one direction, and a pitman rod operatively engaged with the crank 125

shaft and having a loop like portion freely engaged with the rock arm, said loop portion permitting limited movement of the pitman rod with respect to the rock arm but engaging the rock arm to effect an abrupt movement of the rock arm upon nearing the completion of the movement of the pitman rod in one direction, the movement of the figure member in one direction being by gravity.

10 In testimony whereof we hereunto affix our signatures.
